BY

Geo. P. Kimmel
ATTORNEY.

UNITED STATES PATENT OFFICE.

WILLIAM MACDONALD, OF DENNISON, OHIO.

INKING ATTACHMENT FOR COLOR PRINTING.

Application filed May 11, 1928. Serial No. 276,982.

This invention relates to a device or inking attachment for color printing and has for its object to provide, in a manner as hereinafter set forth, a device of the class 5 referred to for enhancing the appearance of impressions obtained from electro-types, zinc etchings, half tones, engraved plates, cuts, etc., by giving color thereto.

A further object of the invention is to 10 provide, in a manner as hereinafter set forth a device of the class referred to for giving color to black and white impressions obtained from electro-types, zinc etchings, half tones, engraved plates, cuts, etc., where- 15 by the impressions will be made unusually attractive, as well as distinctive to readily direct attention thereto.

Further objects of the invention are to 20 provide, in a manner as hereinafter set forth, a device for the purpose referred to which is simple in its construction, compact, durable, thoroughly efficient in its use, inexpensive to set up, automatic in its action, and obtaining the result desired in a thoroughly satisfac- 25 tory manner.

With the foregoing and other objects in view the device consists of the novel construction, combination and arrangement of parts as hereinafter more specifically described and 30 illustrated in the accompanying drawings, wherein is shown an embodiment of the invention, but it is to be understood that changes, variations and modifications can be had which fall within the scope of the claims 35 hereunto appended.

In the drawings wherein like reference characters denote corresponding parts throughout the several views:

Figure 1 is a top plan view of an apparatus for color printing in accordance with 40 this invention.

Figure 2 is a cross sectional view thereof illustrating the arrangement of the device when employing a thick color ink.

Figure 3 is a fragmentary view in plan.

Figure 4 is a fragmentary view in section.

Figure 5 is a fragmentary view in section illustrating the device when employing a thin color ink.

Referring to the drawings in detail 1 denotes an open top container providing a lower reservoir 2 for the ink 3. The side and end walls of the container 1 and which are indicated at 4, 5 respectively are of greater thickness than the thickness of the bottom 6 thereof. The side and end walls 4, 5 are

provided with spaced, vertically disposed openings 7 having threaded walls and which extend from the top to the bottom of the container, and are open at each end. 60

A lid 10 is provided for closing the open top of container 1 and which is formed of an upper section 8 and a lower section 9. The lid generally conforms in contour to the shape of the body of the container 1. 65 Preferably the body of the container 1 is of polygonal contour and the lid 10 has its edges flush with the outer faces of said body.

The section 8 of lid 10 which is the upper section of the latter, is provided in proximity to each of its edges with openings 11 having countersunk walls. The section 9 is flush with section 8 and is formed with openings 12 which register with the openings 11. The section 8 is formed with an opening 13 having a threaded wall and is also formed with an opening 14 having the wall thereof plane. The section 9 is formed with an opening 15 arranged below and of greater diameter than the opening 13. The section 9 is 80 also provided with an opening 16 which is arranged below and of greater diameter than the opening 14. The section 8 is formed with an enlarged circular opening 16' closed at its bottom by section 9 and which in connection with the opening 16' provides an upper reservoir 17. The section 9 has secured thereto a depending intake pipe 18 for the reservoir 17. The pipe 18 opens into the reservoir 2. 85

In Figure 2 the reservoirs 2 and 17 are shown as containing a thick color ink 2' and in Figure 5 reservoir 2 is shown as containing a thin color ink 17' and reservoir 17 empty. When thick color ink 2' is used 95 reservoir 17 is filled completely therewith and reservoir 2 partly filled. Reservoir 17 is not used for thin color ink 17' and when the latter is used reservoir 2 is only partly filled therewith. 100

Fixed to the section 9 and extending upwardly and downwardly therefrom is an outlet pipe 18' for and which opens into the reservoir 2. The pipe 18' extends upwardly through the opening 16 and projects a substantial distance above the section 8. The pipe 18 is disposed centrally with respect to bottom of the reservoir 17 and the pipe 18' is positioned adjacent the axis of such bottom. 105

Mounted on the top of the body portion of the container 1 is a resilient plate 19 corresponding in contour to that of the body por-

tion of the container 1. The resilient plate 19 is interposed between section 9 and container 1 and is formed with an opening 20 which registers with opening 15 and is also formed with an opening 21 which registers with opening 16. The plate 19 is furthermore provided with an opening 22 for the passage of the pipes 18 and 18'. The plate 19 is also provided with openings 23 which register with the openings 12. Seated in the openings 11 formed in the section 8 are the heads 24 of coupling screws 25. The shanks of the screws 25 extend through the openings 12 and 23 and have threaded engagement with the walls of the openings 7, but do not threadedly engage with the sections 8, 9 and plate 19 whereby the lid 10 and plate 19 are slidable relative to the coupling screws 25.

On the application of pressure to the lid 10, 20 the plate 19 will be compressed whereby the lid 10 will slide downwardly and the coupling screws 25 will remain in down position until pressure thereon is released, whereupon the plate 19 will act to restore the lid 10 to the 25 position shown in Figure 2. When the lid 10 shifts on the coupling screws the pipes 18, 18' will be carried therewith. The depression of lid 10 carrying plate 19 and pipes 18, 18' provides for the discharge of thick 30 color ink from reservoir 2 to reservoir 17 and from the latter for color applying to the impression, or for the discharge of thin color ink from reservoir 2 for color applying to the impression, and how such applications are 35 had will be presently referred to.

The pipe 18 is employed for supplying thick ink from the reservoir 2 to the reservoir 17 and when thick ink is employed the pipe 18' is plugged as at 18''. When thin ink is 40 employed the pipe 18 is plugged as at 18'' so that communication is closed between reservoirs 2 and 17. The discharge of the thin ink from reservoir 2 is had through pipe 18', the latter having its plug removed when the 45 apparatus is used in connection with thin ink.

Secured to the wall of the opening 13 and extending through the openings 15 and 20, as well as normally depending below the 50 plate 19, is a peripherally threaded sleeve 26 providing an air intake for the reservoir 2. Operating in the sleeve 26 is a valve stem 27, provided with a valve 28 below sleeve 26. That portion of the stem 27 below valve 28 has 55 mounted thereon a coiled spring 29. In Figure 2 the valve 28 is shown at its uppermost position due to the action of the spring 29 and such position is below the inner end of the sleeve 26. When the lid 10 is depressed 60 the sleeve 26 engages the valve 28 and cuts off the supply of air to the reservoir 2 and on the compression of the lid 10 the ink within the reservoir 2 is either forced into reservoir 17 and discharged therefrom or out through 65 pipe 18' and discharged. When the lid 10

is relieved from pressure the plate 19 moves it upwardly and away from the valve 28 and the action of the spring 29 will restore the valve to its normal position as shown in Figure 2. The pressure of the air within reservoir 2 will act on the ink in the latter for discharging it therefrom, when lid 10 is depressed.

Fixedly secured to the wall of the opening 14 and depending through the openings 16, 75 21 is an interiorly threaded annular sleeve 30, provided with an inset lower portion 31 and which provides a filling tube for the reservoir 2. The sleeve 30 is normally closed by a peripherally threaded plug 32 which has 80 its inward movement arrested by the inset portion 31.

Secured to the section 8 of the lid 10 and extending across the opening 16' is the cut or impression element 33 from which the impression is made. The cut is formed with openings or ports 34 for the passage of ink from reservoir 17 to the upper face of the cut for applying color thereto. Cut 33 is also formed with an opening 35 for the upper end 90 of pipe 18' and when the latter is employed for the discharge of ink from reservoir 2 the color will be applied to the upper face of the cut. To prevent leakage a packing means 36 is interposed between cut 33 and the upper 95 face of section 8 of lid 10, but said packing means does not extend across the top of reservoir 17. The cut 33 may be formed with lines 37 or designs 38, in addition to the original design of the cut and which can be 100 printed in color. The lid 10 provides a resiliently controlled carrier for the impression element.

The feeding or supplying ink to the upper 105 face of the impression element is had automatically when the impression cylinder or plate of the press respectively passes over or bears against the impression element. The openings or ports 34 can be arranged in any suitable manner and of any size. The diameter of the pipe 18' can be as desired. When thin color ink is employed it completely floods the upper face of the cut, but the thick color ink does not, as it spots the impression at spaced points.

It is though that the many advantages of a device or inking attachment for the purpose referred to and in accordance with this invention can be readily understood, and although the preferred embodiment of the invention is as illustrated and described, yet it is to be understood that changes in the details of construction can be had which fall within the scope of the invention as claimed.

What I claim is:

1. A device for the purpose set forth comprising a resiliently controlled pressure operated carrier for a perforated impression element, and means coacting with said carrier for selectively supplying color inks of 130

- different specific gravities through the carrier to the upper face of said element.
2. A device for the purpose set forth comprising a pressure operated carrier for a perforated impression element, a resilient support therefor, and means coacting with said carrier and support for supplying ink through the support and carrier to the upper face of the impression element on the depression of the carrier.
3. A device for the purpose set forth comprising in combination a resiliently supported pressure operated carrier provided with an open top reservoir, a ported impression element secured to the carrier, extended across the top of and communicating with said reservoir, and means coacting with the carrier and the ports of said element for supplying ink to the upper face of the latter on the application of pressure to said element.
4. A device for the purpose set forth comprising in combination a pressure operated carrier provided with an open top reservoir, a resilient support therefor, a ported impression element secured upon the carrier, extended across the top of and communicating with said reservoir, means carrying said support and providing a reservoir below the latter, means for establishing communication between said reservoirs, a discharge pipe leading from the lower reservoir to the upper face of said element, and a controllable air intake for said lower reservoir.
5. A device for the purpose set forth comprising a resiliently supported, pressure operated carrier adapted to have an apertured impression element secured thereon, an ink container having said carrier slidably con-

nected thereon, said carrier and container having coacting means to provide a controllable air intake for the container, and means depending from the carrier to provide for supplying ink to the upper face of said element on the application of pressure to the carrier.

6. A device for the purpose set forth comprising a resiliently supported, pressure operated carrier adapted to have an apertured impression element secured thereon, an ink container having said carrier slidably connected thereon, said carrier and container having coacting means to provide a controllable air intake for the container, and selective means depending from the carrier to provide for supplying ink to the upper face of said element on the application of pressure to the carrier.

7. A device for the purpose set forth comprising a pressure operated carrier adapted to have an apertured impression element secured thereon, an ink container, a resilient support interposed between said carrier and container, means connected to the container and extending through the support for slidably coupling the carrier to the container, said carrier and container having coacting means to provide a controllable air intake for the container, and means depending from the carrier, through said support to provide for the supplying of ink to the upper face of said element on the application of pressure to the carrier.

In testimony whereof, I affix my signature hereto.

WILLIAM MACDONALD.
